CLAIM

[21] Appl. No.: 943,577

The ornamental design for a component for a vehicular loudspeaker, as shown and described.

[22] Filed: Dec. 19, 1986

DESCRIPTION

[52] U.S. Cl. D14/222; D14/221

FIG. 1 is a top, front and left side perspective view of a component for a vehicular loudspeaker showing our new design;

[58] Field of Search D14/204-216, D14/219-224; 181/144, 148, 152, 153, 155, 157, 198, 199; 381/24, 86, 159, 182, 184, 185, 186, 188, 189, 205

FIG. 2 is a top plan view thereof, rotated 90° degrees from FIG. 1;

[56] **References Cited**

FIG. 3 is a left side elevational view thereof, rotated 90° from FIG. 1, the right side being a mirror image; and

U.S. PATENT DOCUMENTS

FIG. 4 is a front elevational view thereof.

D. 280,818 10/1985 Clover, Jr. D14/215
D. 291,988 9/1987 Ishizaki D14/215
D. 295,740 5/1988 Takahara D14/210

The broken line showing of the vehicular loudspeaker is for illustrative purposes only and forms no part of the claimed design.
